UNITED STATES PATENT OFFICE.

CHARLES L. SIMON, OF BEARDSLEY, MINNESOTA.

ROPE HOLDER.

Application filed December 16, 1927. Serial No. 240,549.

The present invention relates to improvements in rope holders and has reference more particularly to a device that provides a connection between a tractor and the free end of the rope that is secured at its opposite end to an earth working implement such as for example, a plow or cultivator.

One of the important objects of the present invention is to provide a rope holder wherein the same is of such construction as to normally connect the tractor with an earth working implement so that both will travel in unison, the rope holder being of such construction as to permit the ready detachment of the rope from the holder when the earth working implement encounters an obstruction.

A further object of the invention is to provide a rope holder of the above mentioned character which is of such construction as to permit the same to be easily attached to a tractor without necessitating any material alterations of the parts of the tractor with which the rope holder is to be associated, said rope holder further including a pair of complementary jaw members that are normally urged in a closed position by means of an expansible spring, one of the jaws being formed with a finger engaging loop to facilitate the separation of the jaws and the insertion or removal of the knotted end of the cord.

A further object is to provide a rope holder of the above mentioned character which is simple in construction, inexpensive, strong and durable and further well adapted to the purpose for which it is designed.

Other objects and advantages of the invention will become apparent during the course of the following description taken in connection with the accompanying drawing.

In the accompanying drawing wherein like reference characters indicate like parts throughout the several views:

Figure 1 is a side elevation of a rope holder embodying my invention showing the knotted free end of a rope held between the jaws.

Figure 2 is a top plan view of the rope holder, and

Figure 3 is a rear end elevation thereof.

In the drawing wherein for the purpose of illustration is shown the preferred embodiment of my invention, the numeral 1 designates generally my improved rope holder, the same comprising an elongated flat

bar 2. The rear end portion of this bar is disposed downwardly as at 3 and thence laterally as at 4, the laterally disposed portion being curved transversely throughout its length to form what I term as the upper jaw 5.

The forward end portion of this bar 2 is bent upwardly as at 6 and thence laterally as at 7, the laterally disposed portion 7 being of greater width than the intermediate portion of the flat strip of metal, and this enlarged forward end portion 7 is also slightly curved in order to permit the same to fit against the curved bottom face of the tractor seat A shown in the dotted lines in Figure 1.

A bolt 8 is adapted to extend through the usual opening formed in the bottom of the seat A, and through a central opening formed in the enlarged forward end portion 7 of the bar 2. A washer 9 is disposed on the upper face of the bottom of the seat and the head of the bolt engages the washer. A nut 10 is threaded on the threaded lower end of the bolt, and the same engages the bottom face of the enlarged forward end portion 7 of the bar 2 whereby to rigidly attach the rope holder to the tractor seat.

A pair of depending ears 11 are formed at the sides of the flat bar 2 adjacent the upwardly bent portion 6 and a bolt or pin 12 extends through the lower ends of these aligned ears for a purpose to be presently described.

An elongated flat metallic bar 13 is formed at its forward end with a knuckle 14 through which knuckle the pin or bolt extends whereby to provide a pivotal connection between the forward end of the lower bar 13 and the upper bar 2 and it is of course to be understood that the lower bar is of less width than the upper bar.

The rear free end portion of the lower strap or bar 13 is bent upwardly as at 15 and is then curved downwardly and forwardly to provide what I term as a finger engaging loop 16. A portion of this loop 16 contacts with the side edges of the transversely curved upper jaw 5 and this portion 17 of the loop provides a lower jaw for cooperation with the upper jaw in the manner that will be presently described. The upper face of the lower jaw forming portion 17 may be provided with an indenture so as to properly receive or engage the rope as shown very clearly in Figure 3.

The intermediate portion of the bar 13

is formed with a longitudinal slot 18 and extending therethrough is the elongated bolt 19, the upper end of the bolt extending through an opening formed therefor in the 5 intermediate portion of the upper bar 2, the head of the bolt engaging the upper face of the upper face as shown more clearly in Figures 1 and 2 of the drawings.

A nut 20 is threaded on the lower threaded 10 end of the bolt and is spaced from the lower bar 13.

An expansible coil spring 21 encircles the lower portion of the bolt 19 and is disposed between the upper face of the nut 20 and 15 the bottom face of the lower bar 13. This spring normally urges the lower pivoted bar 13 upwardly so that the jaw member 17 will be held in engagement with the edge portions of the upper stationary jaw 5. By ad- 20 justing the nut 20 on the threaded end of the bolt, the tension of the expansible coil spring may be regulated.

In use, the knotted free end of the rope B that is secured at its opposite end to the 25 earth engaging implement, not shown, is adapted to be disposed within the rope holder between the complementary jaws 5 and 17, and to this end the finger engaging loop 16 is engaged, and the lower bar 20 13 is swung downwardly against the tension of the spring 21 whereby the jaw 17 is moved away from the jaw 5 and the knotted free end of the rope is inserted between the jaw members. When the finger engaging loop 35 16 is released, the spring 21 will automatically swing the flat bar 30 upwardly and simultaneously force the lower jaw 17 into engagement with the respective side edges of the upper jaw 5 and thereby enclose the 40 knotted end of the rope within the holder so that a positive connection is provided between the tractor (not shown) and the earth working implement (not shown).

Should the earth working implement encounter an obstruction, such as a stone or 45 the like so that the forward movement of the implement is hindered, the pull on the cord will result in the knotted free end being automatically disengaged from be-

tween the jaw members 5 and 17, and in this 50 manner the cord will not break, such as would result in the case where the rope or other towing element was fixedly secured to the tractor.

The provision of a rope holder of the 55 above mentioned character will save considerable time and labor and furthermore due to its simplicity, may be readily and easily attached to a tractor seat without necessitating any material alterations. 60

While I have shown the preferred embodiment of my invention it is to be understood that various changes in the size, shape and arrangement of parts may be resorted to without departing from the spirit of the 65 invention and the scope of the appended claim.

Having thus described the invention, what I claim as new is:—

In a rope holder of the class described, 70 an elongated flat upper bar, the forward end portion thereof being constructed for attachment to a tractor seat, the rear end portion of said bar being constructed to form a transversely curved jaw, depending 75 ears formed at the side edges of the intermediate portion of the upper bar, a lower bar pivotally secured at its end between the lower ends of said ears, the rear end of said lower bar being bent upwardly to form a 80 jaw complementary to the first mentioned jaw, the free end portion of said last mentioned jaw being bent to form a finger engaging portion, a bolt secured at its upper end to the intermediate portion of the upper 85 bar and extending downwardly through the intermediate portion of the lower bar, a nut threaded on the lower end of the bolt, and an expansible coil spring encircling the 90 lower portion of the bolt and disposed between the nut and the lower bar for normally urging the lower bar upwardly to maintain the complementary jaws in engagement with each other to secure the knotted end of the rope therebetween. 95

In testimony whereof I affix my signature.

CHARLES L. SIMON.
